HERMETICALLY SEALED PIEZOELECTRIC
CRYSTAL HOLDER

Harold Granger, Alexandria, Va.

Application December 27, 1940, Serial No. 371,949

16 Claims. (Cl. 171—327)

(Granted under the act of March 3, 1883, as
amended April 30, 1928; 370 O. G. 757)

My invention relates broadly to piezoelectric crystal apparatus and more particularly to a holder for piezoelectric crystal elements by which long-time frequency stability may be obtained.

One of the objects of my invention is to provide a piezoelectric crystal holder in which the crystal is hermetically sealed in order to provide for long-time frequency stability by eliminating the effects of changes in barometric pressure and changes in relative humidity, in addition to the effects of dust and other foreign material.

Another object of this invention is to provide a hermetically sealed holder with provision for externally adjusting the size of the air gap between electrodes.

Another object of this invention is to provide a hermetically sealed externally adjustable holder which may be readily interchangeable with an existing type of holder.

The use of a piezoelectric crystal for frequency control or frequency measurement purposes generally requires that the final adjustment of the frequency be made while the crystal is operating in a suitable circuit. Since in the interest of long-time frequency stability it is desirable to eliminate the effects of changes in barometric pressure and changes in relative humidity, in addition to effects of dust and other foreign materials, it is desirable to provide a holder which can be hermetically sealed; in addition, it is desirable to be able to adjust the air gap between the crystal and one of the electrodes so that final adjustment of the frequency of the unit can be made while operating in its intended circuit. These requirements are met by this device.

My invention will be described in connection with the accompanying drawings, in which:

Fig. 1 is an elevation view of one design of a piezoelectric crystal holder of my invention;

Fig. 2 is a cross-sectional elevation view of the same design taken through the center line;

Fig. 3 is a cross-sectional plan view taken through the line 3—3 of Fig. 2;

Fig. 4 is a cross-sectional elevation view, taken through the center line of a modification of my invention; and

Fig. 5 is a cross-sectional plan view taken through the line 5—5 of Fig. 4. The two different designs are furnished to indicate the possible variations in construction of this device.

With reference to Fig. 2, a glass bead or seal 11 acts as an insulator or dielectric for the electrical connection 22 to the upper electrode 18. The glass bead 11 is sealed to a glass sealing alloy tube 24 which is in turn sweated or welded to

5 a movable assembly consisting of plate 25, upper electrode 18, electrode insulating support 12, terminal insulator 20 and its support 21. This plate and assembly is attached to a metal bellows 15 by welding or soldering and this bellows is in turn attached to the holder housing 19. Adjusting ring 14 bears upon the plate 25 and by rotation of the ring the bellows 15 is made to contract or allowed to expand, the expansion force being supplied by the natural spring of the bellows in addition to that supplied by a coil spring 16. An evacuation or filler port 26 is provided for the purpose of removing the air from the inside of the holder and introducing an inert gas or thoroughly dried air, after which the filler port may be sealed. Machine screws 13 used for supporting the upper electrode assembly are sealed by soldering over the heads.

20 This construction results in a hermetically sealed crystal holder, at the same time permitting external adjustment of air gap 23, thereby providing control of the frequency within limits determined by the characteristics of the crystal 17, which is held by suitable means in contact with the holder housing 19 acting as a lower electrode.

Figs. 4 and 5 portray an additional design. This design is made primarily to provide a hermetically sealed adjustable air gap crystal holder 30 in such form that it would be readily interchangeable with an existing type of holder.

With reference to Figs. 4 and 5, which are sectional drawings of the subject device, a glass bead or seal 30 is bonded to a glass sealing alloy tube 42 which is soldered or welded to a crystal holder casing 44. The glass bead 30 in this case is extended to provide a support for a terminal 31 to which is connected the electrical connection or conductor 32 for the upper electrode 37. The conductor 32 is in the form of a tube and permits the exit or introduction of gas or dry air from or to the interior of the holder, after which the tubular conductor is sealed. The conductor 32 is connected electrically to movable electrode 37 by flexible connector 40. A metal bellows 35 is attached by means of welding or soldering to a metal plate 45 to which is attached an assembly consisting of ceramic insulating support 46 and upper electrode 37. The opposite end of the bellows 35 is soldered or welded to the crystal holder casing 44. Soldering or welding the bottom or fixed electrode 39 to the casing 44 completes the hermetic seal. Machine screws 34 supporting movable electrode assembly are sealed by soldering over 55 the heads. Adjusting ring 33 bearing on plate

45 permits adjustment by contraction or expansion of the bellows 35. Expansion of the bellows is accomplished by the natural spring of same in addition to the force supplied by a coil spring 36. A stud 43 is rigidly secured to and projected from casing 44. The holder is supported by spring clips (not shown) which engage, respectively, terminal 31 and stud 43 and which are connected to an external circuit.

This construction provides a hermetically sealed 10 holder and makes possible adjustment of the air gap 41 above piezoelectric crystal 38 providing a frequency control limited by the characteristics of the crystal.

The use of a hollow electrical connection from 15 the external terminal of the upper electrode, as shown in Fig. 4, is not necessarily limited to Fig. 4, but might also have been used in the construction shown in Fig. 2. Also, the spring 16 in Fig. 2 is shown located inside of the bellows and the corresponding spring 36 in Fig. 4 is shown located 20 outside of the bellows. The location of the spring in either case has no bearing upon any electrical or mechanical properties of the device, but may be placed either inside or outside of the 25 hermetically sealed chamber.

Other modifications and changes in the proportions and arrangements of the parts may be made by those skilled in the art without departing from the nature of the invention, within 30 the scope of what is hereinafter claimed.

The invention described herein may be manufactured and/or used by or for the Government of the United States of America for governmental purposes without the payment of any royalties 35 thereon or therefor.

What I claim is as follows:

1. A piezoelectric crystal holder, comprising in 40 combination a casing acting as a lower electrode, an upper electrode insulated from said lower electrode, said holder adapted to accommodate a piezoelectric crystal in the space between said electrodes, means to vary and adjust the size of said space, and means to hermetically seal said space with said crystal therein.

2. A piezoelectric crystal holder, comprising in 45 combination a casing acting as a lower electrode, an upper electrode insulated from said lower electrode, said holder adapted to accommodate a piezoelectric crystal in the space between said electrodes, external means to vary and adjust the size of said space, means to hermetically seal said space with said crystal therein, and means to connect said electrodes to an electric circuit.

3. A piezoelectric crystal holder, comprising in 50 combination a threaded casing acting as a lower electrode, an upper electrode insulated from said lower electrode, said holder adapted to accommodate a piezoelectric crystal in the space between said electrodes, an upper plate attached to and insulated from said upper electrode, a spring 60 between said lower electrode and said upper plate, a threaded adjusting ring bearing against said upper plate, said threads on said ring adapted to cooperate with said threads on said casing, said adjusting ring being adjustable to vary and adjust the size of said space between said electrodes, means to hermetically seal said space with said crystal therein, and means to connect said electrode to an electric circuit.

4. A piezoelectric crystal holder, comprising in 65 combination an externally threaded casing acting as a lower electrode, an upper electrode insulated from said lower electrode, said holder adapted to accommodate a piezoelectric crystal in the 70 space between said electrodes, an upper plate attached to and insulated from said upper electrode, a spring between said lower electrode and said upper plate, a threaded adjusting ring bearing against said upper plate, said threads on said ring adapted to cooperate with said threads on said casing, said adjusting ring being adjustable to vary and adjust the size of said space between said electrodes, means to hermetically seal said space with said crystal therein, and means to connect said electrode to an electric circuit.

space between said electrodes, an upper plate attached to and insulated from said upper electrode, a spring between said lower electrode and said upper plate, an internally threaded adjusting ring 5 bearing against said upper plate and adapted to cooperate with said external threads on said casing, said adjusting ring being adjustable to vary and adjust the size of said space between said electrodes, means to hermetically seal said space with said crystal therein, and means to connect said electrodes to an electric circuit.

5. A piezoelectric crystal holder, comprising in combination a casing acting as a lower electrode, an upper electrode insulated from said lower electrode, said holder adapted to accommodate a piezoelectric crystal in the space between said electrodes, means to connect said upper electrode to an electric circuit, means to connect said lower electrode to an electric circuit, means to vary and adjust the size of said space between said electrodes, an upper plate attached to and insulated from said upper electrode, a metal bellows between said lower electrode and said upper plate, a hermetic seal at the joint of said bellows and said upper plate, a hermetic seal at the joint of said bellows and said lower electrode, the boundary surfaces formed by said upper plate, said bellows and said lower electrode having an opening, and means to hermetically seal said opening after placing said first mentioned means therein.

6. A piezoelectric crystal holder, comprising in combination a casing acting as a lower electrode, an upper electrode insulated from said lower electrode, said holder adapted to accommodate a piezoelectric crystal in the space between said electrodes, means to connect said upper electrode to an electric circuit, means to connect said lower electrode to an electric circuit, means to vary and adjust the size of said space between said electrodes, an upper plate attached to and insulated from said upper electrode, said upper plate having an opening, means to hermetically seal said opening after placing said first mentioned means therein, a metal bellows between said lower electrode and said upper plate, a hermetic seal at the joint of said bellows and said upper plate, and a hermetic seal at the joint of said bellows and said lower electrode.

7. A piezoelectric crystal holder, comprising in combination a casing acting as a lower electrode, an upper electrode insulated from said lower electrode, said holder adapted to accommodate a piezoelectric crystal in the space between said electrodes, means to connect said upper electrode to an electric circuit, means to connect said lower electrode to an electric circuit, means to vary and adjust the size of said space between said electrodes, an upper plate attached to and insulated from said upper electrode, a metal bellows between said lower electrode and said upper plate, a hermetic seal at the joint of said bellows and said upper plate, a hermetic seal at the joint of said bellows and said lower electrode, said casing having an opening, and means to hermetically seal said opening after placing said first mentioned means therein.

8. A piezoelectric crystal holder, comprising in combination a casing acting as a lower electrode, an upper electrode insulated from said lower electrode, said holder adapted to accommodate a piezoelectric crystal in the space between said electrodes, means to connect said upper electrode to an electric circuit, means to connect said lower electrode to an electric circuit, means to vary and adjust the size of said space

between said electrodes, a glass bead adapted to hermetically seal and surround said first mentioned means, a glass sealing alloy tube adapted to hermetically seal and surround said bead, an upper plate attached to and insulated from said upper electrode, having an opening adapted to receive said tube, a hermetic seal at the joint of said tube and said upper plate, a metal bellows between said lower electrode and said upper plate, a hermetic seal at the joint of said bellows and said upper plate, and a hermetic seal at the joint of said bellows and said lower electrode.

9. A piezoelectric crystal holder, comprising in combination a casing acting as a lower electrode, an upper electrode insulated from said lower electrode, said holder adapted to accommodate a piezoelectric crystal in the space between said electrodes, means to connect said upper electrode to an electric circuit, means to connect said lower electrode to an electric circuit, means to vary and adjust the size of said space between said electrodes, an upper plate attached to and insulated from said upper electrode, a metal bellows between said lower electrode and said upper plate, a hermetic seal at the joint of said bellows and said upper plate, a hermetic seal at the joint of said bellows and said lower electrode, an extended glass bead adapted to hermetically seal and surround said first mentioned means, a glass sealing alloy tube adapted to hermetically seal and surround said bead, said casing having an opening adapted to receive said tube, and a hermetic seal at the joint of said tube and said casing.

10. A piezoelectric crystal holder, comprising in combination a casing acting as a lower electrode, an upper electrode insulated from said lower electrode, said holder adapted to accommodate a piezoelectric crystal in the space between said electrodes, means to hermetically seal said space with said crystal therein, means to connect said upper electrode to an electric circuit comprising a tubular electric conductor adapted to pass through said first mentioned means, means to hermetically seal said tubular conductor, means to connect said lower electrode to an electric circuit, and means to vary and adjust the size of said space between said electrodes.

11. A piezoelectric crystal holder, comprising in combination a casing acting as a lower electrode, an upper electrode insulated from said lower electrode, said holder adapted to accommodate a piezoelectric crystal in the space between said electrodes, means to hermetically seal said space with said crystal therein, means to connect said upper electrode to an electric circuit comprising a tubular electric conductor adapted to pass through said casing, means to hermetically seal said tubular conductor, means to connect said lower electrode to an electric circuit, and means to vary and adjust the size of said space between said electrodes.

12. A piezoelectric crystal holder, comprising in combination an externally threaded casing acting as a lower electrode, an upper electrode insulated from said lower electrode, said holder adapted to accommodate a piezoelectric crystal in the space between said electrodes, means to connect said upper electrode to an electric circuit, means to connect said lower electrode to an electric circuit, a glass bead adapted to hermetically seal and surround said first mentioned means, a glass sealing tube adapted to hermetically seal and surround said bead, an upper plate attached to and insulated from said upper

5 electrode having an opening adapted to receive said tube, a hermetic seal at the joint of said tube and said upper plate, a metal bellows between said lower electrode and said upper plate, a hermetic seal at the joint of said bellows and said upper plate, a hermetic seal at the joint of said bellows and said lower electrode, a spring between said lower electrode and said upper plate, and an internally threaded adjusting ring bearing against said upper plate, said threads on said ring adapted to cooperate with said threads on said casing, said adjusting ring being adjustable to externally vary and adjust the size of said space with said crystal therein.

13. A piezoelectric crystal holder, comprising in combination an externally threaded casing, a lower electrode, a hermetic seal at the joint of said casing and said lower electrode, an upper electrode insulated from said lower electrode, said holder adapted to accommodate a piezoelectric crystal in the space between said electrodes, means to connect said upper electrode to an electric circuit comprising a tubular electric conductor adapted to pass through said casing, means to hermetically seal said tubular conductor, means to connect said lower electrode to an electric circuit, an upper plate attached to and insulated from said upper electrode, a metal bellows between said casing and said upper plate, a hermetic seal at the joint of said bellows and said upper plate, a hermetic seal at the joint of said bellows and said lower electrode, a hermetic seal at the joint of said bellows and said casing, an extended glass bead adapted to hermetically seal and surround said tubular electric conductor, a glass sealing alloy tube adapted to hermetically seal and surround said bead, said casing having an opening adapted to receive said tube, a hermetic seal at the joint of said tube and said casing, a spring between said upper plate and said casing, and an externally threaded adjusting ring bearing against said upper plate, said threads on said ring adapted to cooperate with said threads on said casing, said adjusting ring being adjustable to externally vary and adjust the size of said space with said crystal therein.

14. A piezoelectric crystal holder, comprising in combination a casing acting as a lower electrode, an upper electrode insulated from said lower electrode, said holder adapted to accommodate a piezoelectric crystal in the space between said electrodes, means including a spring to vary and adjust the size of said space, and means including a bellows to hermetically seal said space with said crystal therein.

15. A piezoelectric crystal holder, comprising in combination a casing acting as a lower electrode, an upper electrode insulated from said lower electrode, said holder adapted to accommodate a piezoelectric crystal in the space between said electrodes, means to vary and adjust the size of said space, and means including a bellows to hermetically seal said space with said crystal therein.

16. A piezoelectric crystal holder, comprising in combination a casing acting as a lower electrode, an upper electrode insulated from said lower electrode, said holder adapted to accommodate a piezoelectric crystal in the space between said electrodes, means including a spring to vary and adjust the size of said space, and means to hermetically seal said space with said crystal therein.

HAROLD GRANGER.
